(57) **CLAIM**

The ornamental design for a rope ratchet, as shown and described.

DESCRIPTION

FIG. 1 is a perspective front view showing our new design for a rope ratchet.

FIG. 2 is a front elevation view of the rope ratchet shown in FIG. 1.

FIG. 3 is a back elevation view thereof.

FIG. 4 is a top plan view thereof.

FIG. 5 is a bottom plan view thereof.

FIG. 6 is a right-side elevation view thereof; and,

FIG. 7 is a left-side elevation view thereof.

The irregular broken lines in the figures are included for the purpose of showing contour and rounded features thereof and forms part of the claimed design.
